FEEDING MECHANISM

L. V. Andrews, Worcester, Mass., assignor to Riley Stoker Corporation, Worcester, Mass., a corporation of Massachusetts

Application December 8, 1933, Serial No. 701,468

1 Claim. (Cl. 198—52)

This invention relates to feeding mechanisms, and more particularly to mechanisms of the type comprising a substantially horizontal trough which is vibrated to produce a feed of material 5 along the trough.

It is one object of the invention to provide a simplified construction for a feeding mechanism of the vibrating trough type, to reduce the cost of manufacture, and to ensure continuous and 10 reliable operation.

It is a further object of the invention to combine with the vibrating trough a means for supplying material thereto continuously and without danger of interruption in normal operation, and 15 particularly to so arrange the construction that if a large piece of material should block the feed it can be readily removed.

It is a further object of the invention to combine with the vibrating trough a material supply 20 means which can be easily adjusted to permit operation of the feeding mechanism at maximum capacity with materials of widely different characteristics.

With these and other objects in view, as will be 25 apparent to those skilled in the art, the invention resides in the combination of parts set forth in the specification and covered by the claim appended thereto.

Referring to the drawings illustrating one embodiment of the invention, and in which like reference numerals indicate like parts,

Fig. 1 is a vertical longitudinal section through a feeding mechanism, the section being taken on the line 1—1 of Fig. 2;

35 Fig. 2 is a section on the line 2—2 of Fig. 1;

Fig. 3 is a section on the line 3—3 of Fig. 1;

Fig. 4 is an enlarged view in section showing the rear portion of the vibrating trough;

Fig. 5 is a side elevation of the vibrating trough 40 with the supporting and driving means therefor;

Fig. 6 is a rear elevation of the parts shown in Fig. 5;

Fig. 7 is a top plan view of the rear portion of the construction shown in Fig. 5 with the 45 magnet protecting cover removed; and

Fig. 8 is a perspective view of the rear portion of the vibrating trough.

In the drawings I have shown a feeding mechanism comprising an elongated base 10 provided 50 with three transverse ribs 11 on its upper surface. Three upwardly and rearwardly inclined thin flat springs 12 are fastened at their lower ends to the ribs 11 by means of screws 14. The upper ends of the springs 12 are fastened by means of 55 screws 15 to transverse ribs 16 formed on the

bottom of a horizontal trough 18. The springs form the sole support for the trough, which is free to vibrate in a generally longitudinal direction. The trough is preferably constructed of a comparatively light material, such as aluminum, 5 in order to facilitate the vibrating action.

In order to vibrate the trough 18 I utilize an electro-magnet, and since aluminum is non-magnetic it is necessary to provide a suitable pole piece. For this purpose I form a transverse 10 groove 19 in the rear end of the trough, and I insert in this groove a pole piece 20 which is preferably made of a large number of thin horizontal strips or laminations of iron. These laminations are held firmly in place by means of 15 rivets 21 extending vertically through the pole piece and the adjacent portions of the trough. Directly in the rear of the pole piece 20 is a stationary electro-magnet comprising a core 23 of laminated iron shaped as a letter E with the 20 branches of the E pointed toward the pole piece. The magnet is energized by means of a coil 24 surrounding the central branch of the E and held in place by a strap 25. The core 23 is secured to a bracket 27 which is fastened to the 25 rear portion of the base 10 by means of screws 28. These screws extend through slots 29 in the bracket so that the bracket can be adjusted longitudinally of the base to vary the width of the air gap 30 between the magnet and the pole 30 piece.

If particles of material should become lodged in the air gap 30 they would interfere with the vibration of the trough. In order to avoid this difficulty, I provide a protecting cover plate in 35 the form of a hood 32 fastened to the rear end of the trough 18 and extending rearwardly over the top of the magnet. The hood is shaped as an inverted U, as shown in Fig. 6, and extends downwardly at each side of the magnet. It will 40 be apparent that this hood renders it practically impossible for material from the trough to reach the air gap 30.

My improved feeding mechanism is arranged to deliver material to a chute 34 (Fig. 1) and for 45 this purpose the mechanism is mounted in a casing 35 with the front or discharge end of the trough 18 projecting over the chute. The base 10 is preferably provided with four rubber feet 36 which rest in suitable recesses in the bottom 50 wall of the casing 35, thus supporting the feeding mechanism in the proper position. The casing is closed at the rear by a vertical plate 37 which can be removed to permit withdrawal of 55 the feeding mechanism.

The trough 18 is supplied with material by means of a vertical down-spout 39 arranged to discharge into a hopper 40 supported on the casing 35 directly above the trough. This hopper is provided with a rear wall 42, a front wall 43 and a side wall 44, all of which converge downwardly, and a second side wall 45 which is substantially vertical. The use of the vertical wall 45, in conjunction with the action of the trough in vibrating the mass of material directly beneath the hopper, is decidedly effective in preventing the material from arching in the hopper and thereby obstructing the feed.

The vertical distance between the trough 18 and the lower edge of the front wall 43 of the hopper determines the thickness of the stream of material flowing along the trough to the chute 34, and I have discovered that for any given material there is a definite value for this distance which will provide the maximum feeding capacity. If the distance is either decreased or increased with respect to the said definite value, the feeding capacity will be reduced. Moreover the vertical distance which will result in maximum capacity varies with the type of material being fed, with its fineness, and with its moisture content. In order to make possible high capacity operation with widely differing materials, I provide means for varying the aforesaid vertical distance as may be desired. This is accomplished in the embodiment illustrated by providing a plate 47 which is secured to the wall 43 by means of a thumb screw 48 extending through a slot 49 in the plate. This plate projects below the wall 43 and in effect forms a downward extension of this wall which can be readily adjusted vertically. In order to permit access to the plate 47, a removable closure 51 is mounted above the chute 34, and this closure is provided with a transparent panel 52 through which the feed of the material may be observed. In case a foreign body or a block of material reaches the trough 18 which is too large to pass beneath the plate 47, the plate may be raised and the obstruction withdrawn through the opening 45 provided by the removal of the closure 51. The rear wall 42 of the hopper is preferably provided with an opening 54 for the insertion of a suitable bar or poker to assist in the removal of a possible obstruction.

In order to prevent spilling of material over the sides of the trough, a skirt or apron 56 is provided which in effect forms a downward extension of the two side walls and the rear wall of the hopper. This skirt is preferably formed of thin sheet metal, such as brass, which is smooth and non-corrosive, so that material will not adhere thereto. The skirt extends downwardly into the trough without touching the same, and it is supported by a horizontal flange 57 at its top which is clamped 60 between the casing 35 and the hopper 40. It will be noted from Fig. 1 that the skirt 56 extends forwardly at each side of the trough for a substantial distance beyond the front wall 43 of the hopper, and in fact nearly to the front end of the trough. This makes it possible to maintain a thick mass of material in the trough without spilling, and yet the sides of the trough need not be very high. Hence the trough can be made comparatively light, which is an advantage in a vibrating type of feeder.

It will be apparent that the feeding mechanism can be withdrawn rearwardly from the casing 35 for inspection or repair by first removing the plate 37. In order that this may be done without dropping the material from the hopper 40, I provide

a closure for the bottom of the hopper, and for this purpose I utilize the plate 37. The hopper is formed with grooves 59 at each side directly above the skirt 56, and the plate 37 may be removed from its normal position and thereupon inserted horizontally into these grooves from the rear.

The operation of the invention will now be apparent from the above disclosure. The coil 24 is supplied with a suitable electric current, such as 60 cycle alternating current, which will produce a rapid pulsation in the magnetic flux in the core 23. This will attract and release the pole piece 20 in rapid succession, so that the trough 18 will vibrate in a generally longitudinal direction under the combined influence of the springs 12 and the electro-magnet. Material is delivered to the hopper 40 by the downspout 39, and after descending by gravity into the trough 18 the material is carried along by the vibrating action and deposited in the chute 34. The conveying of the material horizontally is believed to be due in part to the angular arrangement of the springs, which causes the forward movements of the trough to be slightly upward toward the material, and the rearward movements to be slightly downward and away from the material. The action is also believed to be due in part to the fact that the rearward movements of the trough are more rapid than the forward movements, since the rearward movements are brought about by the combined forces of the springs and the electro-magnet, whereas the forward movements are brought about by the springs alone. The inertia of the material being fed apparently prevents it from following the rapid rearward trough movements while allowing it to follow the slower forward movements. Whatever may be the correct theory of operation, it is known that the material will advance toward the chute 34 as the trough is vibrated.

The plate 47 can be adjusted to the height which is found by experiment to produce the maximum rate of feed for the particular material being handled. Thereafter the feeding rate can be reduced if desired by controlling the current flow through the coil 24 in any well-known manner, thus controlling the amplitude of vibration of the trough. In case the feed is obstructed by a large body, the plate 47 can be easily raised or removed to permit withdrawal of the obstruction.

Since the side wall 45 of the hopper is vertical, the material is not held thereagainst by gravity but passes directly downward under the combined action of its weight and the vibration imparted to it by the trough. This prevents any arching of the material between the walls 44 and 45, regardless of the close spacing of these walls, for an arch requires a supporting abutment at each end. The walls 42 and 43 are spaced a considerable distance apart, so that little opportunity is afforded for arching between them. The smooth skirt 56 directs the material into the trough without spillage, and the hood 32 prevents any possibility of particles of material reaching the air gap 30. The arrangement of the electro-magnet at the rear of the trough and the means for mounting the pole piece in the rear portion of the trough combine to produce a very simple, rugged and inexpensive construction.

Having thus described my invention, what I claim as new and desire to secure by Letters Patent is:

A feeding mechanism comprising a substantial- 75

ly horizontal trough, means to vibrate the trough and produce a feed of material along the trough toward the front end thereof, a casing enclosing the trough laterally, a hopper supported by the casing and arranged to supply material to the trough, and a skirt extending downwardly into

the trough from the rear wall and the two side walls of the hopper to prevent spilling of material, the skirt having a horizontal flange at its upper edge which is clamped between the casing and the hopper.
